[57] **CLAIM**

The ornamental design for a light-emitting diode semiconductor chip with leads, substantially as shown and described.

DESCRIPTION

FIG. 1 is a perspective view of a light-emitting diode semiconductor chip with leads showing my new design;

FIG. 2 is a front elevational view thereof;

FIG. 3 is a side elevational view thereof, as seen from the right side of FIG. 1;

FIG. 4 is a side elevational view thereof, as seen from the left side of FIG. 1;

FIG. 5 is a top plan view thereof;

FIG. 6 is a bottom plan view thereof;

FIG. 7 is a perspective view of a light-emitting diode semiconductor chip with leads showing the second embodiment of my new design;

FIG. 8 is a front elevational view thereof;

FIG. 9 is a side elevational view thereof, as seen from the right side of FIG. 7;

FIG. 10 is a side elevational view thereof, as seen from the left side of FIG. 7;

FIG. 11 is a top plan view thereof; and

FIG. 12 is a bottom plan view thereof.
